(57) **CLAIM**

The ornamental design for a cover for a portable air blower, as shown and described.

DESCRIPTION

FIG. 1 is a front elevational view of a cover for a portable air blower showing my new design;

FIG. 2 is a rear elevational view thereof;

FIG. 3 is a left side elevational view thereof, the right side being a mirror image;

FIG. 4 is a top plan view thereof;

FIG. 5 is a bottom plan view thereof; and,

FIG. 6 is a reference view of the cover for a portable air blower, shown in position of use.

A broken line showing of parts of the drawings is included for the purpose of illustrating use and environment and forms no part of the claimed design.
